CLAIM

The ornamental design for a pet chew toy as shown and described.

DESCRIPTION

FIG. 1 is a front right perspective view of a pet chew toy showing our new design.

FIG. 2 is a front elevation view thereof.

FIG. 3 is a rear elevation view thereof.

FIG. 4 is a right side view thereof.

FIG. 5 is a left side view thereof.

FIG. 6 is a top plan view thereof; and,

FIG. 7 is a bottom plan view thereof.

The broken lines depict features of the pet chew toy that form no part of the claimed design.
